United States Patent Office

Des. 195,047

Patented Apr. 16, 1963

195,047

PITCHER

William Marcus, Cleveland, Ohio, assignor to Merrymaid Plastics Corp., Cleveland, Ohio, a corporation of Ohio

Filed Aug. 4, 1961, Ser. No. 66,201

Term of patent 14 years

(Cl. D44—21)

FIG. 1

I claim:

The ornamental design for a pitcher, as shown.
